UNITED STATES PATENT OFFICE.

GEORGE LEE MILLER, OF CANTON, OHIO, ASSIGNOR, BY MESNE ASSIGNMENTS, TO THE
TIMKEN ROLLER BEARING COMPANY, OF CANTON, OHIO, A CORPORATION OF OHIO.

DIE.

Application filed January 26, 1924. Serial No. 688,699.

This invention relates to dies and the objects of the invention are to provide an expansible die for beveling or chamfering the inner edges of the ribs of roller bearing cages to conform to the contour of the rollers.

Roller bearing cages of the general type referred to, are commonly stamped from sheet metal and formed with longitudinal slots to accommodate the rollers.

It is preferable to bevel or chamfer the inner edges of the ribs between said slots, to accommodate the rollers. This is ordinarily accomplished by a very tedious method which requires a separate operation for each slot in the cage and which results in considerable waste of material as well as time.

The present invention contemplates the provision of an expansible die arranged to bevel or chamfer the inner edges of all of the ribs of a cage in a single operation, the die being so constructed that the cage may be easily and quickly centered thereon and finished in a single operation, without danger of spoiling the cage in the beveling or chamfering operation.

An embodiment of the invention is illustrated in the accompanying drawing, in which—

Figure 1 is a vertical section through the improved die, showing the same in the operative position;

Fig. 2, a side elevation of the expansible die;

Fig. 3, a section on the line 3—3, Fig. 2;

Fig. 4, an enlarged fragmentary sectional view through a portion of a cage before the edges are beveled or chamfered; and

Fig. 5, a similar view after the beveling or chamfering operation.

Similar numerals refer to similar parts throughout the drawing.

A roller bearing cage of the type adapted to be operated upon by the improved die is indicated generally at 1. This cage is generally frusto-conical in form to accommodate taper rollers and may be provided at one end with the annular flange 2.

Longitudinal slots 3 are formed in the cage to receive the rollers, these slots being separated by narrow ribs 4. It is found desirable to chamfer or bevel the inner edges of these ribs as at 5 to conform to the curvature of the rollers.

The expansible die to which the invention

pertains, is designed to chamfer or bevel the inner edges of all of the these ribs of the cage in a single operation. This die comprises a plurality of segments indicated generally at 6, forming a conical annulus.

Each segment is provided upon its outer side with the central, inclined portion 7 conforming to the taper of the cage and with the notches 8 at either side of said inclined portion, said notches forming annular grooves entirely around the die to receive the annular coil springs 9.

The vertical edges of the inclined portions 7 of the segments are beveled or chamfered as at 10, conforming to the bevel 5 which it is desired to form upon the inner edges of the ribs of the cage.

The inner face of each segment is inclined as at 11, forming a conical socket to receive the conical plunger 12 which is slidably mounted therein. As shown in the drawings, the plurality of segments, corresponding in number to the slots in the cage, are held together by the annular coil springs 9.

In operating the device to chamfer or bevel the edges of the cage, the above described die is placed within the cage, the segments registering with the slots therein. The cage and die in this position, are then placed within the frusto-conical socket 13 in the die block 14, which is supported upon the table or bed 15 as by the bolster block 16.

The ram 17 of the press is then operated, engaging the upper end of the conical plunger 12 and forcing the same downward through the die, expanding the segments, forcing the beveled portion 7 of each segment into the adjacent slot in the cage, chamfering or beveling the edges of the ribs as shown at 5.

From the above, it will be seen that the inner edges of all ribs in each cage, are beveled or chamfered in a single operation. It will also be seen that the cage may be quickly and easily centered upon the expansible die, the tapered portion of each segment entering the adjacent slot of the cage and as the segments are only held together by the annular springs 9, each segment may move independently of the others to adjust itself to any irregularity in the cage, thus assuring the proper beveling or chamfering of all of the edges.

The improved die not only provides for a considerable saving in time and labor in

the beveling or chamfering of the edges of the ribs, but also eliminates the considerable waste of material which occurs in the method of beveling these edges now in general use.

I claim:—

1. The method of beveling the edges of the ribs of a slotted roller bearing cage, which consists in placing the cage over an 10 expandible die having beveled portions registering with the slots in the cage and expanding said die to bevel the edges of all of said ribs in a single operation by forcing the beveled portions of the die into the slots 15 of the cage.

2. The method of beveling the edges of the ribs of a slotted roller bearing cage, which consists in placing the cage over an 10 expandible die having beveled portions reg-

istering with the slots in the cage, placing 20 the cage in a hollow die and expanding the expansible die to bevel the edges of all of said ribs in a single operation by forcing the beveled portions of the die into the slots of the cage.

3. The method of beveling the edges of the ribs of a slotted roller bearing cage, which consists in placing the cage over an 10 expandible die having a plurality of independently movable, beveled segments registering with the slots in a cage, and expanding said die to bevel the edges of all of said ribs in a single operation by forcing the beveled portions of the die into the slots 30 of the cage.

In testimony that I claim the above, I have hereunto subscribed my name.

GEORGE LEE MILLER.
